TABULATING MACHINE

William W. Lasker, Brooklyn, N. Y., assignor to
Remington Rand Inc., New York, N. Y., a corporation of Delaware

Application July 20, 1931, Serial No. 551,861

4 Claims. (Cl. 235—58)

The present invention relates to punched card accounting systems, and especially to the tabulator mechanisms used in such systems. More particularly, the invention pertains to new mechanisms for transmitting data, obtained by the sensing of a record card, to the computing unit used to tabulate that data.

Until fairly recently tabulating machines of the Powers type were designed to record data appearing on a punched card in a single hole code. It was found, however, that when the minimum spacing, not detrimental to the strength of the card, was used, such a code did not permit the recording of more than 45 columns of information. Consequently, a two-hole code has been put in use. This code provides for 90 columns of information; 45 columns appearing in the upper half, and the remaining 45 columns in the lower half of the record card. It has become customary to designate the two systems respectively as 45 column, or straight, and 90 column, or combination, code. Likewise it has become customary to designate the upper half of the card as the upper 90-column zone, and the lower half as the lower 90-column zone, and to speak of a number of adjacent vertical columns or half columns of the card as a field. Since both the coding systems mentioned above are at present in use, it is desirable to have a tabulator mechanism adapted to sense cards perforated in accordance with either code and to transmit the sensed data to recording mechanism which will properly tabulate it. Up to the present time it has been necessary to tabulate 45-column cards through the use of a tabulator adapted to that code only, and to tabulate 90-column cards on a tabulator adapted to that code alone.

As was stated above, mechanism is already in use whereby a card perforated in accordance with the 90-column code may be sensed and the sensing transmitted to a tabulator head adapted to operate in accordance with that 90-column code. This, however, requires two sets of transmitting elements and two computing units for each vertically adjacent pair of 90-column fields from which data is to be tabulated. There are many times when a single unit will suffice for the two adjacent 90-column fields of the card. An example of such a condition is presented when the price of an article is inserted on a card in a definite 90-column field and that price subsequently changed. In this case a new price may be inserted in the other of the two vertically adjacent 90-column fields, thus making it unnecessary to punch up an entire new card simply because the

price of the article has been changed. In order that the new price may be tabulated in place of the old through the medium of the same computing unit, it is merely necessary that the transmitting elements associated with the new price field be substituted for those associated with the old price field. It will readily be seen that in this manner a single computing unit is used for controlling the accumulation of price, regardless of whether that price is the one originally inserted on the card or a new one subsequently inserted.

The invention thus contemplates a mechanism, insertable between the sensing mechanism and the computing mechanism of a tabulator, which will permit computing mechanism normally adapted to operate from 90-column cards to operate from 45-column cards. In fact, the invention not only provides this, but also provides means to properly tabulate data taken from 45 and 90-column zones and fields of the same card.

The invention also contemplates mechanism, such as that set forth above, which will permit a selection of one of two vertically adjacent 90-column fields to the exclusion of the other for controlling a computing unit common to both.

It is customary to term that mechanism which is insertable between the sensing chamber and the stop baskets of the computing head a "multiple translator" and that term will be used in the following specification.

Likewise, the term "multiple translator section" will be used to designate that portion of a complete multiple translator which is associated with a single computing unit.

It is an object of this invention to provide a multiple translator which will transmit the sensing of a card perforated in accordance with the 45-column code to a computing mechanism adapted to be controlled by cards punched in accordance with the 90-column code and will properly operate that mechanism.

It is a further object of the invention to provide means whereby card fields which lie directly beneath one another, i. e. in the upper and lower 90-column zones of a card, may be selected for tabulation.

A further object of the invention is to provide means whereby a single multiple translator may accomplish both of the foregoing objects. In other words, it is an object of the invention to provide a multiple translator having one section adapted to transmit the sensing of data perforated in accordance with the 45-column code to a tabulator head adapted to operate in accordance with the 90-column code, and having another sec-

tion which is adapted at the same time to select one of two adjacent fields to control the operation of the computing mechanism associated with both those fields.

5 A still further object of the invention lies in provision of means whereby multiple translators may be readily removed from the tabulator and be replaced by others.

10 Other objects and structural details of the invention will be apparent from the following description when read in connection with the accompanying drawings wherein:

15 Fig. 1 is a fragmentary sectional view of a usual form of the well known Powers tabulating machine. This view is so taken that it shows a section through one form of multiple translator section.

20 Fig. 2 is an enlarged broken sectional view of the form of translator section shown in Fig. 1. This view also shows a tabulator stop basket.

25 Fig. 3 is a sectional view of another form of multiple translator section showing the mode of transmitting data in accordance with the 90-column code to computing mechanism arranged to operate in accordance with that code.

30 Fig. 4 is a sectional view of still another form of multiple translator section adapted to select one of two fields, one of which lies beneath the other (the first being in the upper 90-column zone, and the second in the lower 90-column zone) to the exclusion of the other.

35 Fig. 5 is an isometric view of the mechanism shown in Fig. 4; this view shows two translator sections.

40 Fig. 6 is an isometric view of the detail of the mechanism shown in Fig. 5.

45 Fig. 7 is a view of a card showing the numerals from 1 to 9 and 0 represented in both 45 and 90-column codes, the 90-column code representation being shown in both the upper and lower zones of the card.

50 Fig. 8 is a diagrammatic top plan view of a manually operable means for selecting either the upper or lower of two vertically adjacent fields of a 90-column card for tabulation.

55 It should be noted in connection with these figures that a complete multiple translator may comprise a number of identical sections, such, for example, as those of Fig. 2, or a number of dissimilar sections as, for example, those of Figs. 2, 3, and 4.

Coding

In order that the present invention may be more clearly understood, the various codes utilized will be described in detail.

60 The 45-column code is so arranged that each digit is represented by a single hole in a column of the card. All the digits from 1 to 9 as well as zero, 11, and 12, are represented in the 45-column code in the first twelve columns of the card illustrated in Fig. 7; zero appears in the first column, 1 in the second, 2 in the third, etc. up to 11 and 12 which appear in the eleventh and twelfth columns respectively. At the left margin of the card there are Roman numerals which designate the rows of pins of the sensing mechanism.

65 The 90-column code is arranged so that each odd numeral is represented by a single perforation appearing in a half column of the card, or in other words, in a zone of the column. The 90-column code is the same whether the coded representations appear in the upper or lower zone, and is so arranged that each odd numeral is represented by a single hole while each even numeral is represented by two holes, one of which is the

same as that of the next lower odd numeral, and the other that perforation which, if alone, would represent "9".

70 In the upper-90-column zone the sensing pins which will be operated when a card punched to represent numerals is analyzed are as follows: "0"—XII; "1"—XI; "2"—XI and III; "3"—X; "4"—X and III; "5"—I; "6"—I and III; "7"—II; "8"—II and III; "9"—III. These are shown in columns 23 through 32 of the card of Fig. 7.

10 In the lower-90-column zone the sensing pins which will be operated when a card punched to represent numerals is analyzed are as follows: "0"—IV; "1"—V; "2"—V and IX; "3"—VI; "4"—VI and IX; "5"—VII; "6"—VII and IX; "7"—VIII; "8"—VIII and IX; "9"—IX. Representations of the digits appear in columns 58 through 67 respectively, of the card of Fig. 7.

15 Although codes are in use to represent alphabetic characters, they will not be considered here, for the present invention does not contemplate the translation of alphabetic codes.

Sensing mechanism

20 The sensing mechanism is located in the base of the tabulator and is similar to that disclosed in Patent No. 1,245,502 issued to James Powers on November 6, 1917. As is well known, this mechanism is not dependent upon any coding for its 25 functioning, but simply determines whether there is, or is not, a hole in a column of the record card and causes mechanical movements whenever there is a hole present. The sensing mechanism is located in the lower portion of the tabulator 30 (see Fig. 1) and is supported by the base framework 1. The sensing mechanism includes a sensing box 16, which is operated by a cam fastened to the main shaft 5, which shaft is driven from any suitable power source, such as an electric 35 motor.

40 Cards to be sensed are stacked in the magazine 10 (Fig. 1) and a weight placed on top of the stack. A picker knife 11 is connected by a link and cam (not shown) to a roller 6 which rides on a cam 7 fastened to the shaft 5. The cam 7 is shaped so 45 that the knife is reciprocated once during each cycle of the machine. On each forward movement of the picker knife 11, a card is taken from the bottom of the stack and positioned between the right-hand one of the sets of feed rolls 12 and 13, which rolls are driven from the main shaft 5 through gears (not shown). As the rolls revolve, the card is transported into the sensing chamber 14 where it is held due to the action of 50 skid rolls 15 against a card stop (not shown) during a reciprocation of the sensing box 16.

55 During each cycle of the machine, sensing box 16 is elevated under control of the cam on the main shaft, and all sensing pins 17 are brought 60 against the under surface of a card in the sensing chamber 14. Each pin above which there is no hole is moved downward with respect to the sensing box 16 against the tension of its spring 18, which surrounds the sensing pin 17 and is 65 held in place between a shoulder 19 on the pin and the lower plate 20 of the sensing box 16. Each pin above which there is a hole passes through the card and elevates an interponent pin 23 of the interponent pin box 24.

70 The sensing box 1 contains, as is well known in the art, forty-five columns of sensing pins, each column comprising twelve pins, or a total of five hundred and forty. Likewise the interponent pin box 24 contains five hundred and forty pins 23 ar-

ranged in forty-five columns of twelve pins each.

After the card has been sensed the card stop is removed and the skid rolls 15 transport the cards to the right-hand pair of eject rolls 21-22 which pass it on to the left-hand pair and thence to a receiving receptacle.

Computing head

The computing head is mounted on the frame 3 which is supported by the hinge 4 and by the intermediate framework 2, which is in turn supported by the base frame 1. The computing head contains mechanism for accumulating, totaling, and printing data obtained by sensing perforated record cards.

Stop basket

The stop basket with which multiple translator sections of the present invention are designed for use is commonly known as a 90-column stop basket and is shown and described in detail in my Patent No. 1,780,621, dated November 4, 1930. Each stop basket (Fig. 2) comprises a plurality of denominational sets of stops, each such set including four variable stops 30, a fixed stop 31, a special stop 32 and a zero stop 33. The number of denominational sets of stops in a basket varies, but usually lies between the limits of eight and thirteen. Likewise the number of stop baskets varies, the usual number being seven, frequently less, infrequently more.

The variable stops 30 are guided at their lower ends by slots in the stop basket base plate 34, and are held against sidewise movement by pairs of spacers 35 supported by the stop basket frame 36. Each stop 30 is held in its lower position by a spring 37.

The special stop 32 is similarly guided by the base plate 34 and the spacers 35, and is similarly held in its lower position by a spring 37. The upper end of the special stop is provided with a projection which cooperates with fixed plate 38 which extends across the stop basket. The upper ends of the stops 30 are arranged so that when elevated they extend into the path of a projection or heel 44 on an accumulator actuating sector 43, and thus determine the extent of movement of the actuating sectors.

It will be seen that when a stop 30 is elevated alone, it rises into position to permit the actuator to move a definite distance, while if the same stop is elevated together with the special stop 32, all stops lying to the left of the operated stop 30 will be moved further to the left due to the pressure of the heel 44 on the operated stop 30, this movement being permitted because special stop 32 is raised to clear the fixed plate 38. The additional space through which the actuating sector 43 is moved, due to the operation of the stop 32, is equal to the space between two adjacent teeth on the actuator and consequently the actuator is positioned to add the digit represented by the two-hole punching.

Zero stop 33 is normally in its elevated position to hold the actuator at the zero position. The elevation of any stop 30 or of stop 32 causes the slideable cam plate 39 to be moved to the right (Fig. 2) to lower the zero stop 33 and permit the elevated stop to be effected.

It will also be obvious that when the special stop 32 is elevated alone, it will serve simply to depress the zero stop and release the actuating sector which will move until the heel 44 thereon strikes the fixed stop or bar 31 which is so positioned that the actuating sector then comes to

rest in the "9" position. For this reason the stop 32 is frequently called the "9" stop.

Computing mechanism

Each of the type sectors 40 carries numeral types adapted to be imprinted on a record sheet placed on the paper platen 108. All type sectors are pivotally carried on a shaft 64 carried by the frame of the computing head. Each sector 40 is provided with a rearward extension 41 forming a hook to which a spring 42 is attached. The other end of spring 42 is anchored to the toothed actuating sector 43, and tends to displace the sectors 40 and 43 so as to keep a pin 45 which projects from the sector 43 against the end wall 15 of a slot 46 in the sector 40. The teeth of the actuating sector 43 cooperate with a totalizer wheel 47 in the conventional manner. The actuator wheel has a tens transfer tooth 48 which cooperates with a lug on a tens transfer arm 49. During totaling cycles the lug of the arm 49 acts as a stop which limits the reverse rotation of the totalizer wheels and thus determines the position of the sectors 40 and 43 in accordance with the digit which was represented by the totalizer wheel. As was shown when the stop basket was described the actuating sector 43 has a heel 44 adapted, during accumulating cycles, to cooperate with one of a number of stops 30, selected and elevated by the sensing mechanism, or with fixed stop 31.

A type sector 40, an actuating sector 43, a totalizer wheel 47 and a lug carrying tens transfer arm 49 constitute a denominational unit of the computing mechanism of the Powers tabulator. The entire computing mechanism ordinarily comprises seventy denominational units arranged in groups, each group comprising from eight to thirteen units which are cooperatively connected by the tens carrying mechanisms. Such a group 40 will be termed a "computing unit" hereinafter.

An oscillating shaft 54, which is journaled in the frame of the machine carries as many sector shaped cams 55 as there are computing units. Each of the cams 55 is pivotally mounted on shaft 54 but is resiliently connected by pin, slot and spring, with an arm attached to the shaft. A link 57 is pivoted on a stud 56 projecting from cam 55 and extends upwardly and rearwardly to a lever 58 to which it is pivoted. The lever 58 is in turn pivoted on a horizontal shaft 59 and has a curved cam slot 60 in its lower portion. The cam slot 60 embraces a roller 61 on one of a pair of arms 62. The arms 62 are pivotally mounted on the shaft 64 and carry a universal 55 restoring bar 63 which extends in front of the vertical arms of sectors 40 of the computing unit.

During any cycle of operation the cam 55 reciprocates and imparts a forward and upward to-and-fro movement to the restoring bar 63, thereby permitting the sectors to advance and thereafter positively restoring the sectors to initial position. Each sector tends to follow the universal bar 63 on its forward stroke owing to the action of a spring 65 which exerts a downward pull on the end of arm 41. Springs 65 are anchored at suitable points to the tabulator frame. The forward movement of the sector is limited during tabulating cycles by a card controlled stop 30 or 31 and during totaling cycles by the totalizer wheel which is stopped in zero position.

The oscillating shaft 54 is driven through a crank and connecting rod (not shown) from a continuously rotating shaft which in turn is driven from the main shaft 5.

It is believed that the foregoing description of the sensing and computing elements of the Powers tabulator will suffice for the purpose of illustrating the cooperation of the present invention therewith.

Multiple translator

The mechanical movements originated by sensing the data card must be transmitted to the stop baskets to properly operate the stops thereof to control the computing units. Due to the fact that the spacing of the stop baskets differs considerably from the spacing of the pins in the interponent box, and due also to the fact that it may be desirable to arrange data in different order on the ledger sheet than on the card, the stop baskets are separated from the interponent box by a considerable amount and a multiple translator interposed to transmit the mechanical movements resulting from the sensing to the proper stop baskets.

The multiple translator comprises a frame 70 (shown in cross section in Figs. 1, 2, and 4) which is considerably wider at the top than at the bottom (as indicated by the shading in Figs. 3 and 4) and somewhat deeper (distance from side to side Fig. 3) at the bottom than at the top and which is sufficiently high to reach substantially from the interponent box to the stop baskets. When viewed from the front the shape of the multiple translator is that of a shallow U.

Fastened to the multiple translator frame 70 at the base thereof is a perforated guide plate 71 which is of the same size and shape as the plates of the sensing chamber and which has five hundred and forty holes arranged in columns of twelve.

Fastened to the upper edges of the translator frame are a plurality of plates 72, one plate for each stop basket. Each plate 72 has a plurality of rectangular holes in it; these holes being arranged in columns of six each, there being as many columns as there are denominational units in the associated stop basket.

Each multiple translator is thus adapted to contain a plurality of multiple translator sections, various forms of which will be described hereinafter.

90-column multiple translator section

Two translator sections of a form which is in common use are shown in Fig. 3, which is a sectional view through the multiple translator showing but one denominational order of each section.

Each denominational order comprises six interpreter wires 73 guided at their lower ends in six adjacent columnar holes in one half of the plate 71, and at their upper ends in six holes in an upper plate 72. As shown in Fig. 3 the interpreter wires associated with the section of the lower 90-column zone (i. e. those six wires at the left of the view) extend straight upwards and cooperate with a stop basket directly above while those associated with the section of the upper 90-column zone are offset and cooperate with a stop basket located at the left of the computing head. The two stop baskets may be adjacent or remote. The arrangement of the offsets in the interpreter wires of Fig. 3 is purely exemplary; in service the wires associated with the upper 90-column field may be straight and those associated with the lower 90-column field offset, or both may be offset in the same direction, or again both may be offset but in different directions. The amount of offset may vary as between trans-

lating sections, but will always be substantially the same for the different denominational orders of the same section.

Field selecting translator section

The mechanism described above requires a computing unit for each field from which data is to be tabulated and does not permit a single computing unit to be used for data from either of two card fields. However, in accounting practice it is frequently desirable to use a single ledger column to indicate either one of two quantities, and to represent both quantities on the same data card. One example of such a problem is presented in chain store accounting in the practice of which it is customary to price an article twice, once in accordance with its price at the warehouse and the second time in accordance with the price delivered to the retail store.

The present invention contemplates the use of a data card in which the price appears in a given field, and the reprice appears in a vertically adjacent 90-column field; the invention comprises means to select one of the two fields and transmit data therefrom to a common computing unit.

Although price and reprice have been mentioned above it is to be understood that this use is exemplary only and that the invention is intended to be used whenever the data from one of two fields is to be selected for tabulation.

The field selecting translator section is associated with two fields of the record card and it is obvious that a complete multiple translator may include field selecting sections, straight 90-column sections such as those described hereinabove, and 45-90 column sections such as those to be described hereinafter.

Two forms of field selecting translator section are shown in the attached drawings; Fig. 8 shows a manually operable device and Figs. 4, 5, and 6 a card controlled device.

A manually operable field selecting section comprises a plurality (usually five) of interpreter wire 73 for each denominational order of each field, and a special adjustable upper translator plate 75. The special upper plate 75 has for each denominational order of the associated stop basket two columns 76 and 77 of interpreter wire guide holes. Fig. 8 is a fragmentary view of the guide plate 75 indicating schematically the position of the guide holes in relation to the stops 30, 32, and 33 of a single denominational order. Considering now the lowest denominational order only, it will be seen that the five interpreter wires of the lowest order of the price field may be placed in the holes in the column 76 and the interpreter wires of the lowest order of the reprice field in the holes of column 77. Then the price field wires will, in the position shown, register with the stops.

The plate 75 is adjustable along the upper members of the translator frame 70, the amount of adjustment being made equal to the distance between the centers of columns 76 and 77. A knurled headed screw 78 is provided and held in fixed position in respect to the translator frame 70 by a collar or other similar means (not shown). The screw meshes with a screw thread in the plate 75 and as is obvious turning of the screw adjusts the position of the plate. When the plate is moved to the right (Fig. 8) the interpreter wires in the column 77 register with the stops and data from the lowest denominational order of the reprice field will be inserted in the computing unit.

All denominational orders are arranged in the manner described above for the lowest; a unit may comprise any number of orders the usual limits being eight and thirteen.

5 The manually operable field selecting section described above serves its purpose admirably when the cards to be tabulated have been sorted and the plate 75 set in accordance with the field to be tabulated. However, there are times when 10 cards punched in the price field are mixed with cards punched in both the price and reprice field. In such a case means must be provided for automatically selecting one of the two fields for 15 controlling the common computing unit; a translating section for accomplishing this is called an automatic field selecting section.

Cards for controlling the automatic section 20 contain special control holes in the position to permit the operation of the XII pin of the sensing box, samples of such control holes being shown in 25 columns 42-45 of the card of Fig. 7.

Each automatic field selecting translator section (Fig. 5 shows two sections) comprises a plurality of interpreter wires 80, levers 82, stub interpreter wires 85, as well as a lever supporting plate 83, operating lever 89, control wire 92 and plate restoring spring 93.

Fig. 4 is a cross sectional view of the translator and shows in side elevation the parts comprising a single denominational order of the automatic field selecting translator section.

Interpreter wires 80 are generally similar to and operate in the same manner as wires 73 of the lower 90-column unit described in connection 35 with Fig. 3. These wires differ from wires 73 in that they are differently bent and in that they have attached to them the sockets 81. Each socket member 81 is provided with a disc shaped receptacle into which fits the rounded forward 40 end of a lever 82. All levers 82 are of the same length, and each is pivoted on one of the studs 84 on the plate 83. Pivots connected to each lever 82 to the right of its center is a stub interpreter wire 85. These stub wires extend downwardly and occupy the positions of the upper 90 45 column of interpreter wires of Fig. 3.

The plate 83 is slidably mounted on the translator frame 10, the slidable connection being effected in the present example by the cooperation 50 of a shouldered screw 86, inserted in the lower rear member of the translator frame, with a slot 87 in the lug 88 bent over from the plate (see Fig. 5). As is readily seen this construction permits the plate to move vertically a limited amount.

55 Pivots connected to an upper extension of the plate 83 is an operating lever 89 which extends forward and is pivoted at its forward end on a stud 90 held by a bracket 91 which is fastened to the lower front member of the trans- 60 lator frame.

Attached to the operating lever 89 toward the rear thereof, is a special control wire 92 which extends downwardly and is guided by a hole in the lower plate 11 to position to be controlled by 65 a sensing pin in the XII position.

A spring 93 is stretched between a stud 94 on the plate 83 and a stud 95 on the translator frame. This spring serves to hold the plate 83 in its lower position and, therefore, to hold the 70 control wire 92 as well as all stub interpreter wires 85 in lower position.

As is readily seen by referring to Fig. 5, the studs 84 which support the levers 82, are sufficiently long so that the rear ends of all levers associated with the same digit in all denominational 75

orders of the translating section may be pivoted thereto. The sections shown in Fig. 5 have but four denominational orders each, but obviously there might be more.

When a perforation in a price or upper field is 5 sensed the stub interpreter wire 85 corresponding to that perforation is elevated by the elevation of the sensing pin and the corresponding interponent pin 23. The elevation of the interpreter wire 85 swings the connected lever 82 clockwise about its stud 84 and elevates the connected interpreter wire 80 to operate the associated stop. It should be noted that stub interpreter wires 85 do not extend as far below the plate 71 as do the interpreter wires 80. The stops 30 must always 15 be elevated the same amount, and since when operated by the stub interpreter wires 85 there is an increase of movement due to the lever arrangement, only a part of the movement of the 20 interponent pins 24 can be utilized.

When a perforation appears in the reprice or lower 90-column field a control hole appears in the price or upper 90-column field. A sensing pin passing through the control hole elevates an interponent pin 23 and raises control wire 92 25 which causes lever 89 to swing counter-clockwise about its pivot 90, thus lifting plate 83 against the tension of spring 93.

Elevation of plate 83 causes all levers 82 to 30 swing about their forward ends and raise all 35 stub interpreter wires out of contact with interponent pins.

The sensing pin which finds a perforation in the lower field raises the corresponding interponent pin which then directly elevates an interpreter wire 80 to set a stop 30 or 32.

The special control wire 92 is sufficiently long to protrude below the plate as much as the wires 80 in order that plate 83 will be sure to rise before interponent pins of the upper field come into 40 contact with stub interpreter wire 85.

Fig. 6 shows a modification of the automatic field selecting translator section in which provision is made for elevating the control wire 92 through the control of any one of four control 45 holes. Fastened to the wire 92 is a block 96 which carries four pins 97 each adapted to cooperate with a pin 24 in the four denominational orders of the section.

50

45-90 column translating section

As was stated hereinabove cards are frequently punched in accordance with the 45 column code either throughout or in one or a few columns. If the only tabulator available be adapted to operate from 90 column code cards, it is impossible to tabulate such cards and for this reason the 45-90 column translating section, described hereinafter, has been designed.

Fig. 2 is a cross sectional view of the sensing 60 and interponent boxes, translator and stop basket of a tabulator. A single denominational order of a 45-90 column translator section is shown in the mid portion of this figure.

Interpreting wires 100, which are similar to 65 but not identical with wires 73 and 80 previously described, extend from alternate guide holes in the translator lower plate 71 to the guide holes in the associated upper plate 72. These wires, in other words, are adapted to be elevated when 70 a hole representing an odd digit appears in the card, or whenever an interponent pin is elevated by any one of the sensing pins I, III, V, VII, IX.

Each interpreter wire 100, other than the one 75 associated with the IX sensing pin, has fastened

to it a collar 104. The wire 100 associated with the pin IX has fastened to it a flag 102 which lies immediately to the rear of the other wires 100 and is provided with bent over lugs 105 which extend into the spaces between wires 100.

5 Stub interpreter wires 101, guided by holes in the translator guide plate 11, are adapted to be elevated whenever an interponent pin is raised by one of the sensing pins II, IV, VI or VIII. Each 10 stub interpreter wire 101 has fixed to it a block 103 and a sleeve 106.

15 Blocks 103 extend rearwardly (to the right in Fig. 2) from the respective interpreter wires and are provided with holes through which the wires 100 pass freely.

It will be seen that whenever one of the stub interpreter wires is elevated it elevates a block 103 which then presses against the collar 104 and the sleeve 106 and elevates a wire 100 and the flag 102.

20 Let it be assumed that a card punched to represent the digit "7" appears in the sensing chamber. Then the sensing pin VII will be elevated, and through the cooperation of the associated interponent pin 23 will elevate the interpreter wire 100 which is second from the front (left in Fig. 2). The interpreter wire slides freely through the block 103 and thus elevates a single stop 30 which 25 will position the actuating sector 43 properly for indicating the digit assumed.

25 If it be assumed that punching for the digit "8" appears in the card then the operation will differ. In this case sensing pin VIII will be elevated and the stub interpreter 101 which is nearest the front will be elevated carrying with it the block 103 and, therefore, causing flag 102 and interpreter 100 to rise. Flag 102 will cause the foremost interpreter wire 100 to be elevated to operate the special stop 32, the associated wire 100 30 will also rise to cause elevation of the associated stop 30. As was explained when the stop basket was described the actuating sector 43 will advance one additional tooth space due to the elevation of the special stop.

35 45 It will be seen from the foregoing that a complete multiple translator may comprise any number of sections (usually not more than seven) each having a plurality of denominational orders and that the sections may be all of one species or some of one of the species disclosed, and others of another.

45 While I have described what I consider to be a highly desirable embodiment of my invention, it is obvious that many changes in form could be 50 made without departing from the spirit of my invention, and I, therefore, do not limit myself to the exact form herein shown and described, nor to anything less than the whole of my in-

vention as hereinbefore set forth, and as hereinafter claimed.

What I claim as new and desire to secure by Letters Patent is:

1. In a machine of the class described, in combination, a plurality of sets of sensing pins including a control sensing pin, a single set of variable stops adapted to be controlled thereby, a multiple translator section between said sensing pins and said stops, a set of interpreter wires 10 within said section cooperating with said stops and with one of said sets of sensing pins, a set of stub interpreter wires operatively connected to said interpreter wires within said section cooperating with another of said sets of pins and 15 means movable by said control sensing pin for rendering said stub wires ineffective.

2. In a machine of the class described, a plurality of sets of sensing pins and a single actuating sector controllable by either of said sets, interpreter wires intermediate one of said sets of sensing pins and said actuator, means movable relative to said interpreter wires capable of cooperation therewith and also with said other set of sensing pins whereby said actuating sector 25 may be controlled by one set of pins through said interpreter wires or by another set of pins through both said interpreter wires and said means, and means responsive to a special record perforation for moving said movable means to 30 ineffective position.

3. In a machine of the class described, a plurality of sets of sensing pins and a single actuator controllable by either of said sets, interpreter wires between one of said sets of pins 35 and said actuators, stub interpreter wires adapted to be operated by another set of pins, movable members connecting said interpreter wires and corresponding stub interpreter wires so that sensing pins of the second set can operate said interpreter wires, and means to move all said movable members in unison to prevent the sensing pins from operating said stub interpreter wires and thus make the interpreter wires only effective to 40 control the actuators.

4. In a multiple translator for use with a tabulator of the Powers type, a set of interpreter wires, a set of stub interpreter wires, a lever joining each interpreter wire with a corresponding stub interpreter wire, a slidtable plate on which 50 all said levers are pivoted, and means to move said slidtable plate to cause all said levers to pivot about said interpreter wires to move said stub interpreter wires to a position such that they 55 can not be operated by tabulator elements normally effective upon them.

WILLIAM W. LASKER.
